(No Model.)

G. A. PRESTON.
BOTTLE.

No. 558,105.

Patented Apr. 14, 1896.

UNITED STATES PATENT OFFICE.

GEORGE A. PRESTON, OF DUNDEE LAKE, NEW JERSEY, ASSIGNOR OF ONE-
THIRD TO CHARLES M. KING, OF PATERSON, NEW JERSEY.

BOTTLE.

SPECIFICATION forming part of Letters Patent No. 558,105, dated April 14, 1896.

Application filed November 13, 1895. Serial No. 568,852. (No model.)

To all whom it may concern:

Be it known that I, GEORGE A. PRESTON, of Dundee Lake, Saddle River township, Bergen county, New Jersey, have invented certain new and useful Improvements in Bottles, of which the following is a specification.

The object of my invention is to provide a bottle and a stopper therefor so constructed that when the contents are placed in the bottle and the stopper is placed in the neck of the bottle it will be necessary to break off the head of the bottle in order to remove the stopper. The object in constructing such a bottle is to prevent as far as possible the practice of fraudulently deceiving the public by refilling old bottles that have been emptied of their original contents with contents of an inferior quality. As it is alleged that this deceit is frequently practiced by unscrupulous persons and the public are deceived by the appearance of the bottles and the labels, and the manufacturers of the genuine articles being also the losers, the necessity of having a bottle that cannot be used the second time without detection is a want which my invention is intended to supply.

The invention consists of a bottle and stopper constructed as shown in the accompanying drawings, and may be made of glass, earthenware, a composition, or any other suitable material or substance.

In the accompanying drawings, in which similar letters of reference indicate like parts, Figure 1 is a vertical sectional view of my bottle and stopper, showing the position of the lower portion of the stopper when the bottle is filled. Fig. 2 is an enlarged view of stopper. Fig. 3 represents a washer located in the neck of the bottle beneath the lower end of the stopper; and Fig. 4 is a vertical sectional view of part of bottle and stopper, the head of the stopper being broken off.

In the drawings, A represents the bottle, and B the stopper, and L a washer.

45 C is the head of the bottle.

K is the neck of the bottle.

The bottle is made thicker at the neck K than at any other portion, for the purpose of strength, and the head C is secured to the neck K, so as to have at the joint of the neck and the head a thin portion D, extending all

around where the neck and head are connected. Around the inside of the neck and head is provided a screw thread or threads in any desired number, and the upper inside portion of the neck is made to project inwardly, so as to form a shoulder or seat for the washer L and the bottom of the stopper B. I prefer to make the washer L of cork; but any other suitable material may be used. 55

The stopper B consists of the upper portion or head having a neck H, much smaller in diameter than the head and the lower portion F, which is threaded like a screw and is adapted to be screwed into the interior threaded 60 portion of the head and neck of the bottle.

The washer L is lowered into the neck of the bottle until it rests on the shoulder S.

The stopper B, like the bottle A, may be made of glass, earthenware, or any other suitable material or substance. 70

My bottle is used in the following manner in order to secure and accomplish the objects and purposes above set forth: The contents, whether consisting of liquids, powders, pills, &c., having been placed therein in the quantities desired, the washer L is lowered into the neck of the bottle until it rests upon the inwardly-projecting portion or shoulder S. The stopper B is screwed into the head and 80 neck of the bottle until the bottom J of the stopper rests upon the washer L. The head of the stopper B is then broken off at the neck or small portion H of the stopper. The head of the bottle may then be filled with wax or 85 any other suitable substance above the portion of the stopper then remaining in the bottle, and the head and neck may then be covered with a cap of any suitable material to protect the bottle and to prevent the head C 90 from being broken off in moving or transportation.

It is obvious that if the portion of stopper remaining in the bottle is made of glass or earthenware or any similar substance it will 95 be impossible to unscrew it and remove it from the head and neck of the bottle and that the only way to remove it is by breaking off the head C from the bottle.

The head C is so connected with the neck 100 K of the bottle as to leave the thin connecting portion D, so that the head C may be

easily broken off at the part D, when the stopper or the thread portion of the stopper remaining in the bottle may be readily removed.

The neck K of the bottle is made much thicker than the other portion of the bottle, so that it may not be fractured in breaking off the head C. Any suitable cork may then be inserted in the neck of the bottle.

When the head of the bottle is broken away from the neck, owing to the construction of the bottle, which will be readily understood by those skilled in the manufacture of bottles, there will be a clean even break and the bottle will be as useful as any complete bottle.

By the use of the washer L and by the perfect fit of the screw-threads F of the stopper and the screw-threads E in the head of the bottle and the method of sealing the bottle the contents will be preserved from the time of filling, packing, and transportation until contents are to be used, when an ordinary cork or stopper may be used in the neck K.

By the adoption of my improved bottle I claim that the practice of fraud or deceit will be reduced to a minimum, as it will be impossible to remove the threaded portion F of the stopper B without breaking off the head C of the bottle. Consequently if a person purchases a bottle of liquor or other merchandise and finds the bottle intact, with the head C on and the threaded portion F of the stopper therein, he knows that the contents are genuine.

I do not confine myself to any particular size of bottle, as the principle of my invention applies to bottles or jars of any dimension.

With this description of my invention, what I claim is—

1. A vessel of any suitable size, shape or material provided with a head C and a neck K and the connecting portion between the head and the neck thinner and weaker in construction than either the head or neck, so that the head of the bottle may be broken off the interior of the head being provided with a screw-thread, adapted to receive and engage the screw-threaded portion of a stopper, in combination with a stopper provided with a lower screw-threaded portion F, a head 50 and a neck portion II of much smaller dimension the neck being made weak so that the head portion may be broken off at the neck, leaving the lower screw-threaded portion F in the head of the bottle, all constructed substantially as shown and described and for the purpose specified.

2. In a bottle the head C and the neck K connected by a weaker portion D, at which the head of the bottle may be broken off still leaving a complete bottle the head C being provided on the inside with a screw-thread, the neck being provided on the inside with a projection or shoulder S, in combination with the washer L and a stopper B having a head 65 and a weak neck portion II and provided with a lower screw-threaded portion F, adapted to screw into the head of the bottle and rest upon the washer L and the shoulder S, the neck of the stopper being weakly constructed 70 so that the head of the stopper may be broken off, constructed substantially as shown and described and for the purposes specified.

GEORGE A. PRESTON.
